DESIGN FOR A COVER PLATE FOR THERMOMETERS OR THE LIKE

George E. Ford, Rochester, N. Y., assignor to
Rochester Manufacturing Company, Rochester,
N. Y., a corporation of New York

Application February 28, 1938, Serial No. 75,460

Term of patent 7 years

To all whom it may concern:

Be it known that I, George E. Ford, a citizen of Canada, residing at Rochester, in the county of Monroe and State of New York, have invented a new, original, and ornamental Design for a Cover Plate for Thermometers or the like, of which the following is a specification, reference being had to the accompanying drawing, forming a part thereof.

Figure 1 is a front elevation of the cover plate for thermometers or the like, showing my new design.

Figure 2 is a side elevation thereof.

Figure 3 is an end elevation thereof.

I claim:

The ornamental design for a cover plate for thermometers or the like, as shown.

GEORGE E. FORD.
